UNITED STATES PATENT OFFICE

132,571

DESIGN FOR A NUMERAL SET OF CANDLE HOLDERS

Arno Scheinpflug, Woodside, N. Y.

Application July 30, 1941, Serial No. 102,568

Term of patent 14 years

To all whom it may concern:

Be it known that I, Arno Scheinpflug, a citizen of the United States, residing at Woodside, in the county of Queens and State of New York, have invented a new, original, and ornamental Design for a Numeral Set of Candle Holders, of which the following is a specification, reference being had to the accompanying drawing forming part thereof, in which—

Fig. 1 is a front elevational view of a numeral set of candle holders, showing my new design; and

Fig. 2 is an enlarged isometric view of a single unit thereof.

I claim:

The ornamental design for a numeral set of candle holders, substantially as shown.

ARNO SCHEINPFLUG.
